UNITED STATES PATENT OFFICE.

JOHN E. HENES, OF MENOMINEE, MICHIGAN.

AUTOMATIC FEEDING APPARATUS.

1,199,181.

Specification of Letters Patent. Patented Sept. 26, 1916.

Application filed April 3, 1913. Serial No. 758,557.

To all whom it may concern:

Be it known that I, JOHN E. HENES, a citizen of the United States, residing at Menominee, in the county of Menominee and State of Michigan, have invented certain new and useful Improvements in Automatic Feeding Apparatus, of which the following is a specification, reference being had to the accompanying drawing, forming a part thereof.

This invention relates to automatic feeding apparatus for automatically delivering packages or receptacles from a supply to some receiving member or apparatus.

15 In the embodiment of the invention illustrated by the drawings accompanying this specification and forming a part hereof, a bottle feeding apparatus is shown for supplying or feeding bottles to a well-known form of automatic bottle filling machine.

20 Referring to the drawings, on which the same reference characters are used to designate the same elements wherever they may appear in each of the several views, Figure 25 1 is an elevation of the apparatus, parts being broken away; Fig. 2 is a plan view of the apparatus, parts being broken away; and Fig. 3 is an elevation on the line $a-a$ on Fig. 2, looking in the direction indicated by the arrows, parts being shown in section.

25 Referring specifically to the drawings, the reference numeral 1 designates the rotatable ring of a well-known type of bottle filling machine which is rotated in practice by suitable mechanism (not shown) and carries the bottle supports 2 which are in the nature of small platforms provided with upstanding guards 3 behind bottles which may be thereon. Seven bottles, only, are indicated by 30 dotted lines on Fig. 2 of the drawings and they are designated by the reference numerals 4, 5, 6, 7, 8, 9 and 10, respectively, for convenience in describing the operation of the apparatus.

45 The apparatus generically consists of a conveyer for the bottles and which may move without moving the bottles under certain conditions, a turntable mechanism for receiving the bottles from the conveyer and 50 placing them on the bottle filling machine and mechanism for driving the conveyer at a suitable speed.

The reference numeral 11 designates a table supported by an upright 12 upon a bracket 13. The table is provided with fixed guides 14 and 15 and with movable guides

16 and 17 which may be held in adjusted positions by thumb-screws 18 and 19. The movable guides 16 and 17 are intended to be adjusted for different sized bottles and are 60 intended to guide the empty bottles centrally upon the conveyer composed of the three chains 20, 21 and 22. The fixed guides 14 and 15 are intended to prevent the bottles being pushed out of line and off the chains 65 sidewise. One end of the table 11 is enlarged in the form of a circular disk and the fixed guide 14 extends around a part of the circumference of this disk. A turntable, or more accurately speaking, a turnstile mechanism A is rotatably mounted by 70 pivot or pin 23 concentrically with the disk part of table 11. This turnstile mechanism A comprises the pillar 24 with the flange 25 slightly elevated above the table to clear the 75 throw-out spring 26 which is secured to the table by bolt 27. Studs 28 are secured to flange 25 and on these studs are pivoted arms 29 which are yieldingly movable against the tension of springs 30 in one direction about 80 studs 28 but which are normally held by said springs 30 against stops 31 projecting upwardly from flange 25, whereby the arms 29 can be utilized to drive and rotate the turnstile mechanism A to remove the bottles 85 from the disk part of the table 11 onto the bottle supports 2. The top of the table 11 and its disk part are set to lie in the same horizontal plane as the bottle supports 2 when said bottle supports are in their 90 lowermost positions, and a part of the disk of the table is cut away in a curve of circular form at 32 to conform to the path of movement of the bottle supports 2 so that the bottle supports can move close to the 95 table in a manner which will be readily understood from the drawings. Each arm 29 is preferably formed with a front wall 33 to contact with bottles and push them around the disk part of table 11 onto the bottle supports 2, a guard flange 34 and strengthening flanges 35 and 36. Flange 25 of turnstile 100 A extends practically to the curve 32 where the disk part of the table 11 is cut away so that arms 29 project over bottle supports 2 105 and the guards 3 on the bottle supports 2 can contact with arms 29 to rotate the turnstile A. The guard flanges 34 are cut away so as to clear the guards 3 on the bottle supports 2, a shoulder 37, however, being left to 110 be engaged by a guard 3 to drive or rotate the turnstile.

The chains composing the conveyer are maintained in a horizontal plane by the table 11 and to provide for the even transfer of the bottles from the conveyer onto the 5 disk part of the table, the chains are let into grooves 38, 39 and 40 in the top of the table so that the tops of the chains project only slightly above the table. The chains are stretched by sprocket wheels 41 and 42 and 10 are driven from shaft 43 by sprocket wheels 44, 45, 46 and 47 by sprocket chains 48 and 49 or equivalent driving mechanism. The shaft 43 may be driven in any suitable or preferred manner but in the construction 15 illustrated it is intended to be driven from a rotatable part of the bottle filling machine (not shown). This driving mechanism does not require to be timed to the rotation of the bottle filling machine because 20 the conveyer chains 20, 21 and 22 can move whether the bottles supported thereon move therewith or not. A cap 50 of approximately the diameter of flange 25 may be secured to the turnstile A for the sake of 25 appearances and this cap will also serve as a protector to prevent broken glass, etc., from falling onto flange 25.

The fixed guides 14 and 15 are spaced apart far enough to receive the largest bottles to be handled by the apparatus and the 30 space between flange 25 of the turnstile A and the extension of the fixed guide 14 which extends around the edge of part of the disk part of the table 11 is also wide enough 35 to receive the largest bottles to be handled by the apparatus. When smaller bottles are to be handled a proper sized filling piece 51 can be slipped between the fixed guide 14 and turnstile A to keep the bottles in proper 40 engagement with arms 29, and clips 52 and 53 may be provided to hold the filling piece in place. A bail 54 may be provided to guard against bottles tipping over as they are moved outwardly onto bottle 45 supports 2.

The operation of the apparatus is as follows: The bottle filling machine being in operation, the bottle supports 2 successively pass the turnstile A and the upstanding 50 guards 3 on the bottle supports 2 successively engage with the shoulders 37 on the arms 29 thereby rotating the turnstile A and moving bottles around with it on the disk part of table 11 until each bottle is removed 55 from table 11 onto a bottle support 2. The throw-out spring 26 extends over the path of movement of the bottle supports 2 to insure the complete placing of the bottles upon the bottle supports and this spring 60 yields inwardly when contacted by the

guards 3. The conveyer consisting of the chains 20, 21 and 22 is in motion tending to move bottles thereon toward the turnstile A. The bottles may be placed upon the conveyer by hand or fed thereto by any suitable delivery mechanism. The guard flanges 34 on the arms 29 are in function filling pieces to partly close the spaces between the arms 29 so that only a single bottle can be pushed into the space between any two arms. 70 The chains 20, 21 and 22 will run or slide under bottles thereon if the row of bottles is kept from moving by the foremost bottle being stopped by flange 25 or a guard flange 34 of the turnstile A. The speed of movement of the conveyer chains 20, 21 and 22 is really immaterial provided they move fast enough to move a bottle into the space between two arms 29 while that space is at rest opposite the opening between the fixed 80 guides 14 and 15 as clearly shown by Fig. 2 of the drawings. The movement of the turnstile A is not a continuous movement but a step-by-step movement as will be readily understood. The springs 30 permit the 85 arms 29 to yield if by chance a bottle too large to pass between flange 25 and filling piece 51 (or fixed guide 14, in case no filling piece is being used) is fed to the apparatus or if a broken bottle or other thing should 90 tend to wedge in the apparatus.

What is claimed is:

1. In turnstile mechanism for automatic feeding apparatus, the combination with a fixed table of a flange revolvably mounted thereon above the same, arms pivoted to the flange and extending radially therefrom beyond its edge and over the table, and yieldable means for holding the arms in their radial positions unless they are opposed by an abnormal resistance. 95

2. In turnstile mechanism for automatic feeding apparatus, the combination with a fixed table of a flange revolvably mounted thereon above the same and provided with studs and stops, arms pivotally mounted upon the studs, and springs for normally holding the arms against the stops with the arms extending radially out beyond the edge of the flange and over the table, the arms being provided with vertical front walls and rearwardly extending guard flanges at their outer ends. 105

In witness whereof I hereto affix my signature in presence of two witnesses.

JOHN E. HENES.
